HOWARD J. KERR, OF WESTFIELD, AND HARRY E. MELTON, OF JERSEY CITY, NEW JERSEY, ASSIGNORS TO THE BABCOCK & WILCOX COMPANY, OF BAYONNE, NEW JERSEY, A CORPORATION OF NEW JERSEY

VAPOR GENERATING UNIT

Application filed July 10, 1929. Serial No. 377,099.

This invention relates to a vapor generating element of a boiler adapted for high boiling point liquids and to a boiler comprising a multiplicity of such elements. The boiler is 5 of the type that comprises headers having dead-end tubes or elements which project downwardly into the furnace and are heated by the hot gases.

The invention will be understood from the 10 description in connection with the accompanying drawing in which Fig. 1 is a side view of the vapor generating element; Fig. 2 is a similar view with parts broken away and part in section; Fig. 3 is a section on an 15 enlarged scale along the line 3—3 of Fig. 1; Fig. 4 is a section along the line 4—4 of Fig. 6; Fig. 5 is a vertical section partly broken away, showing the connection of an element to a boiler header; Fig. 6 is a vertical 20 section along the lower portion of the vapor generating element and Fig. 7 is a vertical section through one of the individual tubes of the vapor generating element showing a twisted metal strip or displacer in 25 position.

In the drawing, reference character 1 indicates the bottom wall of a boiler header of a well known type that is installed to lie 30 in a horizontal direction. A connector 2 is provided which is connected to the header 1 and extends through the lower wall thereof for some distance into the header. The connector 2 may be screwed into a hole by means 35 of screw threads 3 extending through the header wall and may be welded, as indicated at 4, to insure against leakage.

The lower end of the connector 2 is enlarged, as indicated at 5, and a circular plate 6 is welded to the enlarged portion 5, as indicated 40 at 7.

A number of circumferentially disposed vapor generating tubes 8 have their upper ends extending through the circular plate 6 and are welded in place, as indicated at 9. 45 A central tube 10, which is preferably larger than the tubes 8, has its upper end extending through the central portion of the circular plate 6 and is welded to this circular plate, as indicated at 11.

50 The bundle of vapor generating tubes 8

are twisted to bring adjacent tubes into contact with each other and also in contact with the tube 10, as indicated in Fig. 3, thus shielding the tube 10 from direct contact by the hot gases. The slightly helical arrangement of the vapor generating tubes 8 caused by the twisting provides for expansion, and by providing greater flexibility and more uniform distribution of heat tends to obviate bowing or warping, which frequently is the case with tubes of rigid construction when subjected to uneven heating. It will be understood that a plurality of elements may be used for each header of the mercury boiler, these elements being connected to the lower sides of the drums or headers of the boiler in rows. The tubes or units may be arranged in any other relative relation, if desired.

A necked fitting 12 is provided with a 70 central upwardly extending tube 13 to the upper end of which the lower end of the tube 10 is welded, as indicated at 14. A somewhat cup-shaped end cap 15 has the upper edge of its flange welded to the outer 75 edge of the necked fitting 12, as indicated at 16. A conical projection 17 is provided in the bottom of the cup-shaped end cap 15 at its center and passages 18 extend from the projection 17 to positions below the 80 lower ends of the tubes 8 that extend through the fitting 12 and are welded thereto, as indicated at 19.

The tubes 8 may be provided with spiral strips 20 extending from one end to the 85 other to act as displacers for the high boiling point liquid and also to cause the high boiling point liquid and vapor to move in a spiral path while passing upwardly.

A downcomer 21 extends through the central opening in the circular plate 6 and its lower open end extends to the opening in the necked fitting 12 and is free to move up and down according to expansion and contraction. The outside diameter of the downcomer 21 is somewhat smaller than the inside diameter of the tube 10, thus leaving an annular space 22 between the downcomer 21 and the tube 10. Through this annular space 22 high boiling point liquid can pass 100

to assist in shielding the downcomer 21 from excessive heat in the furnace. Spacers 23 may be attached to the outside of the downcomer 21 to keep the same in position inside 5 of the tube 10. The upper end 24 of the downcomer 21 is bent and extends through the side wall of the connector 2 on the inside of the header 1 and is welded in place, as indicated at 25.

10 The end of the stem 26 of an umbrella type separator 27 may be attached to the bent portion of the downcomer 21 by welding the same thereto, as indicated at 28.

The operation is as follows:

15 High boiling point liquid passes from the header downwardly through the downcomer 21 out of its lower end and then along the annular space 22 between the downcomer 21 and the tube 10. Mercury also passes into 20 the lower ends of the tubes 8 which are contacted by the hot gases, thereby generating vapors which rise through the connector 2 and strike the separator 27, any unvaporized high boiling point liquid again passing 25 down through the downcomer 21 and the vapors collecting in the header or passing out of it to a place of use.

By means of this invention more surface 30 can be provided for the generation of vapor in a mercury boiler, as the necked-in construction of the top section of the element where it enters the header, permits the elements to be spaced closer together in the header, thus providing more surface per 35 unit of furnace without affecting the strength of the header as the tube holes are smaller, and by a multiplicity of small tubes arranged in a cylindrical bunch, the necessity for cores or displacers does not exist 40 providing the tubes are of a sufficiently small diameter. By twisting the vapor generating tubes so that they contact with each other and with a central tube, expansion and contraction are provided for and the vapor 45 generating tubes provide a shield for the central liquid downcomer. Also by providing an annular space between the central liquid downcomer and a central tube of slightly larger diameter located concentrically around the downcomer, high boiling 50 point liquid can pass therethrough, thus providing an additional shield for the central liquid downcomer from the hot gas. The combined shielding effect of the vapor generating tubes and the annular space surrounding the liquid downcomer obviates the necessity of providing insulating material 55 between the outer vapor generating tubes and the inner high boiling point liquid supply tube.

We claim:

1. A vapor generating device for a boiler adapted for high boiling point liquid comprising a downcomer, junction fittings, a tube 60 surrounding a portion of said downcomer

leaving an annular space between them, and a plurality of tubes circumferentially disposed around said first named tube, said downcomer and tubes cooperating in the junction fittings. 70

2. A vapor generating device for a boiler adapted for high boiling point liquid comprising a downcomer, a tube surrounding a portion of said downcomer leaving an annular space between them, a plurality of tubes circumferentially disposed around said first named tube, a lower junction fitting connecting said plurality of tubes with the downcomer and a connection from said last named tubes to said boiler, the upper end of said downcomer extending through a wall of said connection. 75

3. A vapor generating device for a boiler adapted for high boiling point liquid comprising a downcomer, a tube surrounding a portion of said downcomer, a tube surrounding a portion of said downcomer leaving an annular space between them, a plurality of tubes circumferentially disposed around said first named tube, and means 80 to provide communication between the lower open ends of said tubes and said downcomer. 85

4. A vapor generating device for a boiler adapted for high boiling point liquid comprising a downcomer, a tube surrounding a portion of said downcomer leaving an annular space between them, a plurality of tubes circumferentially disposed around said first named tube, and a lower junction 90 fitting connecting said plurality of tubes with the downcomer each end of all of said tubes being open. 95

5. In a boiler adapted for high boiling point liquid, a header, a group of tubes connected to said header, a downcomer within said group of tubes, means to provide an annular space around said downcomer and supply liquid to said space, and a junction fitting connecting the downcomer with said group of tubes. 105

6. In a boiler adapted for high boiling point liquid, a header, a group of tubes connected to said header, a downcomer within said group of tubes, means to provide an annular space around said downcomer and supply liquid to said space, said group of tubes being arranged spirally around said downcomer and shielding it from hot gases, and a junction fitting connecting said downcomer with said group of tubes. 115

7. In a boiler adapted for high boiling point liquid, a header, a group of tubes connected to said header, a downcomer within said group of tubes having its lower end free to expand downwardly, means to provide an annular space around said downcomer and supply liquid to said space, and a junction fitting connecting said downcomer with said group of tubes. 125

8. A vapor generating device, comprising, a header plate, a junction fitting with a reduced upper portion extending through the header plate and having an open upper 5 end projecting beyond the header plate for the escape of vapors, a downcomer tube having a liquid collecting opening in the side of the junction fitting, a junction fitting at the lower end of said downcomer tube, and 10 a series of riser tubes between the two junction fittings closely arranged in contact with each other around the downcomer tube for the protection of the same from intense heat.

15. 9. A vapor generating device comprising, a header plate, a junction fitting having an open upper end extending beyond the header plate for the escape of vapors, a downcomer tube having a liquid collecting opening in the side of the junction fitting, a junction fitting at the lower end of said downcomer tube, and a series of riser tubes between the two junction fittings closely arranged in contact with each other around 20 the downcomer tube for the protection of the same from intense heat.

10. A vapor generating device comprising, top and bottom junction fittings, a downcomer tube extending between the fittings, and a series of riser tubes arranged 30 closely around said downcomer tube and substantially in contact with one another to protect the downcomer tube from intense heat and provide fluid passages between the junction fittings, one of said fittings connecting the lower ends of said riser tubes 35 to the lower end of said downcomer.

11. A vapor generating device comprising, top and bottom junction fittings, a downcomer tube extending between the fittings, and a series of riser tubes arranged spirally 40 closely around said downcomer tube to protect the same from intense heat and provide fluid passages between the junction fittings, the spiral arrangement taking care of the 45 relative expansion between the downcomer tube and the riser tubes, one of said fittings connecting the lower ends of said riser tubes to the lower end of said downcomer.

50

12. A vapor generating device comprising, top and bottom junction fittings, a downcomer tube extending between the fittings, and a series of riser tubes arranged spirally closely around said downcomer tube 70 and substantially in contact with one another to protect the downcomer tube from intense heat and provide fluid passages between the junction fittings, the spiral arrangement taking care of the relative expansion 75 between the junction fittings and the downcomer tube and the riser tubes, one of said fittings connecting the lower ends of said riser tubes to the lower end of said downcomer.

13. A vapor generating device for high 80 boiling point liquids comprising junction fittings, a downcomer supported by one of said fittings at its upper end and free to expand downwardly, a tube surrounding a portion of said downcomer leaving an annular space 85 between them, and a plurality of tubes in the other of said junction fittings and circumferentially disposed around said first named tube and connected by said last named fitting to the lower end of said downcomer. 90

14. A vapor generating device adapted for high boiling point liquids comprising a downcomer, a tube surrounding a portion of said downcomer and leaving an annular space 95 between said tube and downcomer, an upper junction fitting supporting said downcomer, a plurality of tubes circumferentially disposed around said first named tube, and a lower junction fitting connected to the plurality of tubes and said downcomer. 100

15. A vapor generating device for high boiling point liquids comprising a downcomer, a tube surrounding a portion of said downcomer and leaving an annular space 105 between them, and a plurality of tubes extending spirally around said first named tube, and means connecting the lower ends of said tubes to the lower end of said downcomer.

CERTIFICATE OF CORRECTION.

Patent No. 1,919,335.

July 25, 1933.

HOWARD J. KERR, ET AL.

It is hereby certified that error appears in the printed specification of the above numbered patent requiring correction as follows: Page 2, lines 85 and 86, claim 3, strike out the words and comma "a tube surrounding a portion of said downcomer, "; and that the said Letters Patent should be read with these corrections therein that the same may conform to the record of the case in the Patent Office.

Signed and sealed this 5th day of December, A. D. 1933.

F. M. Hopkins
